UNITED STATES PATENT OFFICE.

JOHAN M. ANDERSEN, OF BOSTON, MASSACHUSETTS, ASSIGNOR TO ALBERT & J. M. ANDERSEN MANUFACTURING COMPANY, OF BOSTON, MASSACHUSETTS, A CORPORATION OF MAINE.

ELECTRIC-CIRCUIT CONTROLLER.

1,250,754.

Specification of Letters Patent. Patented Dec. 18, 1917.

Application filed April 29, 1914. Serial No. 835,324.

To all whom it may concern:

Be it known that I, JOHAN M. ANDERSEN, a citizen of the United States, residing in Boston, county of Suffolk, and State of Massachusetts, have invented an Improvement in Electric-Circuit Controllers, of which the following description, in connection with the accompanying drawings, is a specification, like characters on the drawings representing like parts.

This invention relates to an electric circuit controller or switch, especially adapted among other uses to be employed in circuits carrying currents of substantially large volume, and has for its object to provide the same with means for locking the movable member of the switch in its closed position, so as to prevent accidental opening of the switch. Provision is made for operating the locking means by a detachable handle, and for preventing said handle from being disengaged from the movable member of the locking mechanism with the switch in its closed position, until the operator has actuated the handle to move the locking mechanism into its operative or locking position.

These and other features of this invention will be pointed out in the claims at the end of this specification.

Figure 1 is a front elevation of one construction of switch provided with a locking mechanism embodying this invention.

Fig. 2, a plan of Fig. 1.

Fig. 3, a side elevation of Fig. 1.

Figs. 4 and 5, details of a handle for locking and unlocking the switch as will be described, and

Figs. 6 and 7, diagrammatic views to be referred to.

In the present instance, I have shown the invention as embodied in one form of switch, which is of known construction and comprises a stationary terminal plate or bar *a* having arms *b* to which are pivoted at *c* a plurality of blades *d*, herein shown as three in number, which constitute the movable member of the switch herein shown, and which coöperate with three pairs of contact arms *e*, secured to a terminal plate or bar *f*, arranged in the same plane as the terminal bar *a*.

The movable member *d* of the switch, in accordance with this invention, is designed to be locked in its closed position shown in Figs. 1 and 3, by a locking mechanism, which

may and preferably will be made as herein shown and comprises two coöperating members, one of which is attached to the terminal bar *f* and the other to the free end of the movable contact member *d*.

The member attached to the terminal bar *f* may be designated the stationary member of the locking mechanism, and the member attached to the blades *d*, the movable member of said locking mechanism. The movable member of the locking mechanism herein shown, comprises a cross head or bar 10 on one end of a rotatable cylindrical rod or bolt 12, which is mounted to turn in a cap or tie bar 13, secured to the ends of the blades *d* of the movable switch member, and is provided at its front end with a substantially flat head 15, having on its underside a socket or opening 16 for the reception of a lug or projection 17 on a bar or rod 18, preferably provided with a substantially long handle 19 of insulating material, which rod is detachable from the movable member of the switch. The rod 18 and its handle 19 will be hereinafter referred to as the detachable handle.

The cross head 10 of the movable member of the locking mechanism coöperates with two fingers or hooks 20, on arms 21, extended from a back plate 22 secured to the terminal bar *f* and constituting the stationary member of the locking mechanism. The fingers 20, are separated from each other by a space of a width greater than the thickness of the cross head 10, so that, when the latter is in its unlocked position substantially at right angles to the position shown in Fig. 2, the said head may be passed freely between the fingers 20, to permit the movable member of the switch to be moved into and out of its operative position.

The movable member of the locking mechanism has coöperating with it one or more springs 24, which are secured to the cap 13, and have their free ends engaged with the head 15 of the bolt or movable locking member 12, to retain the latter in its operative and inoperative positions against accidental movement.

Switches of the character herein shown are frequently located on a wall or support away from the operator, to safeguard the latter and other persons, and the handle 18, 19 is made detachable to remove danger of the circuit being opened or closed by unau-

2

thorized persons, and also because it is impracticable to have the handle permanently attached to the switches of this character under certain conditions. To make sure 5 that the operator has turned the bolt or locking member into its operative position after closing the switch, provision is made for preventing the handle 18, 19 from being disengaged from the bolt 12, until the latter 10 has been turned into its fully operative or locking position. To this end, the cap 13 has extended from it at one side thereof, an arm 30, which is arranged at one side of and below the longitudinal center of the 15 bolt 12, and which coöperates with the head 15 of the bolt, when the switch is closed and the bolt in its inoperative or unlocking position, to prevent the handle being disengaged from the bolt, as represented in Fig. 6. 20 The arm 30 also acts as a stop for the bolt and limits rotation of the bolt, when the cross head 10 has been positioned behind the fingers 20, and for this purpose, it is engaged by a finger 31 on the head 15 of the bolt. 25 By reference to Fig. 2, it will be seen that when the finger 31 rests upon the arm 30, the cross head 10 is behind the fingers 20 and the movable member of the switch is locked in its closed position. When the 30 finger 31 rests upon the arm 30, the socket 16 in the bolt head 15 is on the underside of the bolt and in position to have the lug 17 of the handle extended into it. The arm 30 prevents further rotation of the bolt beyond the locking position of the latter as 35 the finger 31 in the rotation of the bolt is brought down upon the arm 30. The stop arm 30 also serves to notify the operator when the bolt is in its locking position. 40 The operation of the locking mechanism 45 may be briefly described as follows: Assume that the switch is in its closed position shown in Figs. 1, 2 and 3, and that it is desired to open the switch. The operator inserts the lug 17 on the handle 18, 19, into the 50 socket 16, which is now on the under side of the head 15, and turns or twists the handle so as to rotate the bolt into a position substantially at right angles to the position shown in Fig. 2, and into its unlocking position, with the cross head 10 of the bolt disengaged from the fingers 20 and free to pass between them. The head 15 is now in a 55 position to present the socket 16 toward the arm 30, and thus confine the handle between the said arm and head, as represented in Fig. 6, and prevent the handle from being moved laterally sufficiently to withdraw the stud or projection from its socket 16 in the 60 head 15. When the bolt is in its unlocking position just described, sufficient space exists between the head 15 and the arm 30, to permit the handle 18 to be turned on the stud or projection 17 as a pivot, which 65 enables the operator to pull the movable mem- ber *d* of the switch downwardly through an arc of over 90° or into a position indicated in Fig. 7. In this downward movement, the arm 30 is practically moved with relation to the handle 18, so that the latter no 70 longer extends between the head 15 and arm 30, and is confined by the same against material lateral movement as represented in Fig. 6, but extends away from the arm as shown in Fig. 7, and is not opposed by 75 the latter, and consequently can be moved laterally away from the head 15, so as to withdraw the lug or projection 17 from the socket 16, and thus disengage the handle 80 from the bolt.

To close the switch, the lug 17 is inserted into the socket 16, and the movable switch member *d* is moved upwardly from the position indicated by Fig. 7, into that indicated by Figs. 6 and 1, and when the switch member *d* is in its closed position, the handle cannot be disengaged from the bolt until the operator has turned the bolt into its locking position shown in Figs. 1, 2 and 3, and the operator is thus obliged to lock the switch in 90 its closed position before he can disengage the handle from the bolt. When the switch is locked in its closed position, it cannot be opened by the current when a short circuit occurs in the circuit in which the switch is 95 included.

In the present instance I have shown one construction embodying the invention, but it is not desired to limit the invention to the particular construction shown, although it 10 may be preferred.

Claims:

1. The combination with a circuit controller provided with a movable member, of means for locking said movable member in 10 its closed position, said means comprising a rotatable bolt movable bodily with said movable member and provided with a cross head, and stationary devices with which said cross head coöperates, substantially as described. 11
2. The combination with a circuit controller provided with a movable member, of means for locking said movable member in its closed position, said means comprising a rotatable bolt movable bodily with said movable member and provided with a cross head at one end, and with a socketed head at its opposite end, stationary devices coöperating with said cross head, a stationary stop arm coöperating with the socket head to arrest 12 rotation of said bolt in one direction, and a finger carried by said bolt and coöperating with said stop arm, substantially as described. 13
3. The combination with a circuit controller provided with a movable member, of a rotatable bolt carried by said member, means coöperating with said rotatable bolt to lock the said member in its closed position, a handle detachable from said bolt and capable of being engaged therewith to effect 14

rotation of the bolt, and means coöperating with said bolt to prevent disengagement of said handle from said bolt when the switch is closed and unlocked.

5. 4. The combination with a circuit controller provided with a movable member, of a rotatable bolt carried by said member and provided at one end with a cross head and at its other end with a socket, and stationary 10 devices separated for the passage between them of the cross head in one position, and with which said cross head engages when the latter is in another position.

5. The combination with a circuit controller provided with a movable member, of a locking bolt carried by said member and mounted to rotate thereon, and stationary 15 means coöperating with said rotatable bolt

to positively lock the movable member in its closed position.

6. The combination with a circuit controller provided with a movable member, of means for locking said movable member in its closed position, said means comprising a rotatable bolt movable bodily with said 25 movable member and provided with a head, and a stationary device with which said head directly engages.

In testimony whereof I have signed my name to this specification in the presence of 30 two subscribing witnesses.
